G. C. STACY.
AUTOMATIC FEED CONTROL.
FILED JAN. 22, 1921.

UNITED STATES PATENT OFFICE.

GROVER C. STACY, OF DALLAS, TEXAS.

AUTOMATIC FEED CONTROL.

Application filed January 22, 1921. Serial No. 439,239.

To all whom it may concern:

Be it known that I, GROVER C. STACY, a citizen of the United States, residing at Dallas, in the county of Dallas and State of Texas, have invented certain new and useful Improvements in Automatic Feed Controls, of which the following is a specification.

This invention relates to new and useful improvements in automatic feed controls.

10 In the feeding of cotton thru an air conduit to a cotton cleaner or other preliminary handling machine, it frequently occurs that the machine either stops or slows down so that it becomes choked with cotton, as the 15 person feeding the cotton into the conduit is not aware that the machine has stopped or slowed down. Such an occurrence causes a great delay as the machine must be cleaned out before operation can be resumed.

20 The object of my invention is to provide an automatic cut off in the cotton conduit or flue controlled and operated by means of a governor which is revolved by one of the 25 shafts of the cotton cleaner or other machine; and whereby a cotton cleaning flue will be closed by means of a suitable valve or the like when the speed of the governor is reduced to such a point as to operate said valve.

30 A construction designed to carry out the invention will be hereinafter described together with other features of the invention.

The invention will be more readily understood from a reading of the following specification and by reference to the accompanying drawings, in which an example of the invention is shown and wherein:

Fig. 1 is a plan view of a device constructed in accordance with my invention,

40 Fig. 2 is a cross-sectional view showing the valve mechanism,

Fig. 3 is a cross sectional detail of the governor collar mechanism,

Fig. 4 is a cross sectional detail on the 45 line 4—4 of Fig. 1, and

Fig. 5 is a longitudinal sectional detail of the sliding collar of the governor.

In the drawings the numeral 10 designates a revolving shaft which may be part of a 50 cotton cleaner or other machine, which shaft is revolved when the machine is operated. I mount a governor on this shaft which comprises a collar 11 suitably fastened on the shaft and a sleeve 12 slidable on said shaft 55 toward the collar 11, and being limited in

such sliding movement by a collar 13 adjustably fastened on the shaft. A pair of spring arms 14 are attached on one end to the collar 11, and at the other ends to the sleeve 12. Each arm 14 is preferably made 60 of spring metal and carries a weight 15 at its center on its outer side. Coiled springs 16 have their ends suitably attached to the weight. When the shaft is revolved the collar 11 will revolve the arms 14 and the centrifugal action will cause the weights 15 to move radially whereby the arms 14 will be extended or bowed as is shown in dotted line in Fig. 1. When the weights 15 are swung outwardly the sleeve 12 will be drawn toward the collar 13. 70

The sleeve 12 has a circumferential groove 17 in which a split ring 18 is confined. The ring has a radial port 19 connected with a compression grease cup 20. The sleeve 12 75 has radial ports 21 adapted to pass under the port 19 when the sleeve is revolved and thus supply lubrication to that portion of the shaft about which the sleeve rotates.

A lever 22 has a slot 23 near its inner end 80 receiving a pin 24 whereby the lever is pivoted and arranged to undergo longitudinal movement. The pin is carried by a guide plate 25 mounted on suitable supports 26 and having stops 27 at its upper end limiting the swing of said lever, the pin 24 being at the inner end of the plate. The inner end of the lever has an eye 28 receiving a bolt 29 and engaging in a V-shaped notch 30 formed in an ear 31 on the ring 18. It will be seen 90 that when the sleeve 12 is pulled toward the collar 13 the lever 22 will be swung so that its outer end will be carried to the left as shown in dotted lines in Fig. 1.

In the cotton feeding flue 32 I mount a 95 rectangular frame 33 in which a gate 34 is arranged to slide vertically. A flexible connection such as a small cable 35 is connected to the gate and extends up over a pulley 36. The pulley 36 is mounted at the upper end 100 of a standard 37 which straddles the flue and is supported on a cross beam 38. The cable 35 extends from the pulley to the outer end of the lever 22.

Under ordinary conditions when the machine to which the shaft 10 is attached is idle and no cotton is being fed, the parts will occupy the position shown in full lines in Fig. 1. However, when motion is imparted to the shaft the collar 11 will be re- 110

volved and the spring arms 14 of the governor will be thrown outward by reason of the centrifugal action and the weights 15. The arms 14 will expand in opposition to the tension of the coiled springs 16, and thus will not reach their maximum expansion or extension until the shaft 10 has attained its normal speed of revolution. When the governor is operating the sleeve 12 will be pulled toward the collar 13 and the ring 18 which does not rotate will be carried with the sleeve; consequently the lever 22 will be swung on its pivot 24 so that its outer end will be moved to the left. When the lever 22 is swung the cable 35 will be pulled, whereby the gate 34 will be raised and the flue 32 opened so that the cotton may pass to the machine operating the shaft 10. So long as the machine continues to operate under normal conditions the gate 34 will be held suspended and the parts will occupy the position shown in dotted lines in Fig. 1. However, should the machine cease to revolve the shaft 10 at its normal speed, the 25 governor would contract thus sliding the sleeve 12 away from the collar 13 and swinging the lever 22 whereby the gate 34 would be lowered. If the gate was lowered but half way in the flue the feed would be cut 30 down and it would be seen that the feeding of the cotton is thus regulated. Should the machine stop altogether the arms 14 would be completely retracted by the coiled springs 16 and the lever 22 would be swung 35 so as to entirely close the gate 34 and thus cut off the feed of cotton and prevent choking of the machine. It will be apparent that the device is entirely automatic in its operation and will be very sensitive and quick to either reduce the feed or entirely 40 cut off the same by closing the gate 34. Just as soon as the machine is again started the governor will operate, swing the lever 22

and raise the gate 34, whereby the flue will be opened and the feed resumed.

Changes in the dimensions and modifications and alterations may be made without departing from the spirit of the invention.

What I claim, is:

1. In an automatic feed control for cotton treating machines, the combination with the revolving shaft of a cotton treating machine and the air suction flue leading to the said machine, of a cut off mounted in said flue, a centrifugal governor mounted on the shaft and having a sliding element, a lever having connection with the sliding element of the governor, and a connection between the lever and the cut off for operating said cut off when the lever is swung by the governor.

2. In an automatic feed control for cotton treating machines, the combination with a revolving shaft of the cotton treating machine and the air suction feeding flue leading to said machine, of a gate arranged to close said flue transversely, a centrifugal governor mounted on the shaft and including a sliding element, a pivoted lever having connection at one end with the sliding element of the governor, and a connection between the other end of the lever and the gate for elevating said gate when the lever is swung.

3. In an automatic feed control, a governor including expanding revolving members and a sliding element, a ring carried by the sliding element of the governor, a lever having its inner end pivoted to the ring, a vertically sliding gate, a frame for supporting the gate in a cotton flue, and a flexible connection extending from the gate to the outer end of the lever.

In testimony whereof I affix my signature.

GROVER C. STACY,
